UNITED STATES PATENT OFFICE

HANS GUBBEI, OF PHILADELPHIA, PENNSYLVANIA

COLLAPSIBLE BED

Application filed May 23, 1929. Serial No. 365,258.

My invention relates to new and useful improvements in a collapsible bedstead and has for its object to provide the collapsing of the bedstead into a relatively small space and yet when it is opened up for use, it will be equally rigid as a non-collapsible bedstead.

A further object of my invention is to construct the bedstead as to render it equally adaptable for the use of grown persons or for young children.

With these and other ends in view, this invention consists in the details of construction and combination of elements hereinafter set forth and then specifically designated by the claim.

In order that those skilled in the art to which this invention appertains may understand how to make and use the same, I will describe its construction in detail, referring by numerals to the accompanying drawings forming a part of this application, in which:

Fig. 1, is a side elevation of the bedstead in its collapsed condition.

Fig. 2, is a similar view of the bedstead adjusted for use.

Fig. 3, is an end view of Fig. 2 showing the upper side frames partly swung down in dotted lines.

Fig. 4, is an end view of Fig. 1.

Fig. 5, is a plan view of a portion of the bedstead, partly collapsed.

In carrying out my invention as herein embodied, 10 represents the corner posts of the bedstead to which are hinged as at 11 the sectional end frames 12, each pair of said sectional end frames being hinged together as at 13.

14 represents the side frames, each of which extends between and connects two of the posts so that when the bedstead is collapsed by swinging the end frames inward, as indicated in Fig. 4, and partially in Fig. 5, the side frames, and posts will collapse upon the end frames, thus bringing the entire bedstead into a space represented by the thickness of two posts and two end frames, making it exceedingly convenient to store in a closet or other shallow space, or in an alcove of a wall, therefore, especially adapting it for

use in small rooms where space is limited.

When the bedstead is adjusted for use, the placing of the ordinary mattress carrying a rigid frame, upon the bottom rails 18 of the side frames will lock the frames in their open positions, making the bedstead as rigid as though it were not collapsible, as will be readily understood.

Where it is desirable to use the bed for small children, a secondary side frame 14^a may be utilized in which case the secondary side frames are hinged as at 15 and these secondary frames are held in position when the bedstead is adjusted for use by the thumb screws 16 passing through the posts and into the top rails 19 of said frames, but when the bed is to be used by older persons, the secondary side frames are removed or omitted.

The top rails of the end frames have the extensions 17 formed therewith which project over the upper ends of the posts and preferably contact therewith in order to increase the rigidity of the bedstead when in its open adjustment.

While I have shown my bedstead as of plain straight line design, it is obvious that it may be made of various designs more or less ornamental and therefore I do not wish to be limited to the exact details of construction as herein shown, as these may be varied within the limits of the appended claim without departing from the spirit of my invention.

Having thus fully described my invention, what I claim as new and useful is:

In a bedstead of the character described, two pairs of posts, two side frames, each of the latter connecting one pair of posts, sectional end frames, each section being hinged to one of the posts, the inner ends of each pair of end frames being hinged together and an extension formed with each section of the end frames, said extension projecting over the upper ends of the posts for contact therewith to increase the rigidity of the bedstead when in its open adjustment.

In testimony whereof, I have hereunto affixed my signature.

HANS GUBBEI.
